Design U.S. Appl. No. 29/627,919, filed Nov. 30, 2017 (Self et al.).

Primary Examiner — Ian Simmons*Assistant Examiner* — Mark Cavana(74) *Attorney, Agent, or Firm* — Lerner, David,
Littenberg, Krumholz & Mentlik, LLP(57) **CLAIM**

The ornamental design for a reagent plate, as shown and described.

DESCRIPTION

FIG. 1 is a front perspective view of a reagent plate showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines illustrate unclaimed portions of the cuvette tray and form no part of the claimed design. The dot-dash broken lines represent unclaimed boundaries and form no part of the claimed design.

1 Claim, 3 Drawing Sheets(56)
